UNITED STATES PATENT OFFICE.

ANDREW LITTLE, OF NEW YORK, N. Y.

DESIGN FOR FONT OF PRINTING-TYPES.

Specification forming part of Design No. 7,910, dated December 1, 1874; application filed October 19, 1874.
[Term of Patent 7 years.]

To all whom it may concern:

Be it known that I, ANDREW LITTLE, of the city, county, and State of New York, have invented and originated a new and original Design for Printing-Type, of which the following is a specification:

The nature of my design is clearly shown in the accompanying typographic impression, to which reference is made; and consists in shading what is designated as "old-style" printing-type, substantially as shown.

What I claim as new is—

The design for a font of printing-type, as shown.

ANDREW LITTLE.
